ROTARY ENGINE

Verner E. Sprouse, Columbus, Ind.

Application April 27, 1945, Serial No. 590,585

5 Claims. (Cl. 253—50)

1

This invention relates to a rotary type engine wherein a gaseous fluid is applied from a common flow point intermittently around the periphery of a rotor for a limited circumferential distance, then collected and again applied around an additional circumferential length of the periphery of the rotor in a different phase relation than in the first application. The engine might be termed a multiple expansion rotary engine operating in a more or less positive manner as opposed to a simple impingement of fluids against members on the rotor.

A primary object of the invention is to obtain the maximum possible power from a minimum size unit with a relatively high efficient use of the operating fluid. A still further important object of the invention is to provide an exceedingly simple structure with but one moving part, the rotor.

An advantage arising from the invention is that the rotor may be built in a cast form rather than having to employ inserted buckets or the like, all to the end that the rotor construction be exceedingly durable over long periods of usage and under high temperatures.

These and many other objects and advantages will become apparent to those versed in the art in the following description of one particular form of the invention as illustrated in the accompanying drawings, in which

Fig. 1 is a view in perspective of one side of the engine;

Fig. 2, a view in front elevation with a power drive pulley applied;

Fig. 3, a view in side elevation of the engine 35 and rotor with the power drive face plate removed;

Fig. 4, a view in perspective of the engine with the power drive side plate removed and also the rotor removed;

Fig. 5, a view in corresponding perspective of the rotor;

Fig. 6, a view in perspective looking from front to rear of the engine body from the power drive side thereof; and

Fig. 7, a view in perspective of the rotor viewed in the same relation as that view of Fig. 6.

Like characters of reference indicate like parts throughout the several views in the drawings.

I form a body 10 which is essentially an annulus with a supporting base 11 on its under side and with an extending portion 12 at its upper side, in which portion 12 is formed a fluid receiving cell 13.

On each side of a centrally disposed rib 14 55

2

are disposed a plurality of what may be termed expansion cells 15. The diameter of the rib 14 is the diameter of the internal opening through the body 10. This rib 14 extends around from the leading edge 16 of the cell 13 which opens into the annulus, then is carried circumferentially around to the exhaust port 17. On the other side of the exhaust port 17, continuing circumferentially around the body, is a full width curved area 18 which continues on around to the trailing edge 19 of the cell 13, the radius of curvature of this area 18 being the same as the radius of curvature of the rib 14. The cells 15 are provided in regular manner in the body 10 on each side of the rib 14 and are aligned one with the other transversely of the rib 14 to have the transverse edge portions 20 terminating in the inner face of the rib 14. It is to be noted that, going in a clockwise direction, Figs. 3, 4, 15 and 6, the cells 15 have first an arcuate portion entering back into the body 10 and from which portion the cell is bounded by a substantially flat area sloping back to the transverse margins 20 the distances between which are equal for all cells 15. The rib 14 forms a boundary wall between the cells 15 positioned on each side thereof.

Spaced circumferentially around the body 10 on the inner side thereof, substantially half way between the opening from the cell 13 and the exhaust port 17 are a pair of what I term booster cells 21, being symmetrically positioned one on each side of the rib 14. Each cell 21 is approximately symmetrical with the cell 15, but is much larger in size, being not only radially deeper, but also having a longer circumferential length. The distance between the terminal edge portions 20 at each end of the booster cell 21 is greater than the distance between those edge portions of the cell 15, but less than twice that distance.

Continuing in a clockwise direction from the transverse edge portions 20 of the booster cells 21, the body 10 is further provided with a plurality of expansion cells 22 regularly spaced on around to the exhaust port 17, and laterally aligned one with another on each side of the intervening rib 14. These cells 22 are of the same length and of the same configuration and depth as the cells 15. It is to be noted however, that by reason of the spacing of the transverse edges of the booster cells 21, the transverse edges defining the ends of the cells 22 are out of phase in effect with the spacing of the transverse edges 20 of the cells 15. This will be further explained hereinafter.

Within the body 10 is mounted a rotor gener-

ally designated by the numeral 23. A shaft 24 is fixed to the rotor to extend from each side thereof and be carried in suitable bearings mounted in the cover plates 25 and 26, the shaft having a length to extend through one of the plates at least to have some driving means mounted thereon, herein shown as the pulley 27, Fig. 2.

The rotor 23 is provided with a central rib 28 to have a diameter which will run in very close proximity with the face of the rib 14 of the body 10, and this rib 28 has a width substantially matching that of the rib 14 sufficient to retard to some degree lateral flow of fluids between those two ribs. On each side of the rib 28, the rotor is provided with a plurality of what I term power cells 29. These power cells 29 preferably have substantially the same configuration and are of the same sizes of the expansion cells 15 and 22 in the body 10. These power cells 29 terminate with laterally disposed edges 30 on a circumference which will carry them across in close proximity with the corresponding edges 20 of the body cells 15 and 22. In the rotor 23 the power cells 29 on one side of the rib 28 are staggered circumferentially in respect to the cells 29 on the other side so that the terminal ends 30 of the cells 29 on the one side will be substantially midway between the ends 30 on the other side.

The two side plates 25 and 26 sealably enclose the rotor 23 therebetween and within the body 10, some sealing means being provided against radial flow of the operating fluid along the side faces of the rotor 23 to the shaft 24 so as to withhold the operating fluid from entrance into the bearings carrying the shaft 24. One such sealing means may comprise a circular rib 31 carried by the cover plate to enter with a running fit into a circular groove 32 provided around the rotor 23.

Also, these two side plates 25 and 26 enclose the admittance cell 13 from each side so that flow therefrom is confined to flow toward the periphery of the rotor 23. A fluid admittance port is had through either the body 10 or one of the side plates 25 and 26 to carry fluid into the cell 13, such a port 33 being herein provided, for example, in the plate 25. A suitable exhaust pipe 34 may be attached to the engine to conduct exhaust externally from the port 17 in any direction as may be desired.

In operation the operating fluid, be it steam, air or gases of combustion, is admitted into the cell 13 under pressure. The only escape from that cell 13 is toward and against the periphery of the rotor 23. Due to the configuration and arrangement of the expansion cells 15 and the power cells 29, the rotor 23 will revolve in a clockwise direction in reference to Figs. 3-7. As is indicated in Fig. 3, one of the power cells 29 has its trailing portion open to the cell 13.

Therefore, the compressible fluid then in the cell 13 may flow into that cell 29 which is open under the transverse leading edge 16. In the position of the rotor 23 as shown in Fig. 3, the fluid may flow into that first cell 29 under the edge 16, and thence be directed by reason of the curved end wall of the cell 29 outwardly and into the first expansion cell 15 immediately adjacent the edge 16, following which the flow may continue from that cell 15 ahead into the next adjacent power cell 29 on the rotor 23, thence outwardly into the succeeding expansion cell 15 and so on around the rotor 23 until the fluid escapes into the booster cell 21.

With the rotor still in the same relative posi-

tion as shown in Fig. 3, the transverse edge 20 across the leading end of the cell 21 is then in registry with the transverse edge 30 of a rotor power cell, thereby substantially sealing off further flow of the fluid circumferentially around the rotor 23, and this flow is so stopped by reason of the fact that in that instantaneous position of the rotor 23, the following transverse edges 30 are in substantial registry with the housing edges 20. However, since a compressible and expansible fluid is employed, the outflowing fluid in the cell 21 will exert a thrust to continue the clockwise travel of the rotor 23 by pressure against the end walls of the rotor cells 29, particularly in respect to the cell 15 adjacent the leading edge of the booster cell 21.

Then following sufficient travel of the rotor 23 to bring a transverse edge 30 into registry with the trailing edge 20 of the booster cell 21, a transverse edge 30 will have travelled on beyond and out of registry with the leading edge 20 of the cell 21, and in like manner all of the subsequent cell edges 30 will be out of registry with the subsequent cell edges 20 around to the exhaust port 17 so that the fluid shall be free to travel through its tortuous passageway around the periphery of the rotor and in and out of the cells of the body 10 until the fluid may finally escape at a very muchly reduced pressure through the exhaust port 17. It is to be noted when the escape through the exhaust port 17 is permissible, flow from the cell 13 is arrested by reason of the trailing edges 30 of the respective cells 29 being in registry with the leading edges 20 of the cells 15 between the cell edge 16 and the trailing edge 20 of the booster cell 21.

While this action is going on on the one side of the transverse ribs 28 and 14, the same action is going on on the opposite side of those ribs, but only in a delayed sequence by reason of the staggered arrangement of the cells 29 on the rotor 23. In other words, when the cell 29, as shown in Fig. 3, is open to the cell 13 under the edge 16, the corresponding cell on the other side of the rib 28 is substantially sealed off from the cell 13 by having its trailing edge under and possibly slightly toward the leading side of the cell edge 16.

Thus it is to be seen that by the unique positioning of one set of expansion cells 15 out of phase in relation to another subsequent set of cells 15 in relation to the regular spacing of the cells 29 around the rotor 23 permissible by the intervening booster cells 21, an advantage is gained by preventing a free flow of the fluid in its zig-zag passage around the rotor and body to the exhaust port, and instead of that free flow, the flow is interrupted momentarily to permit the utilization of the expansion of the fluid in two stages.

While I have herein shown and described my invention in the one particular form, it is obvious that structural changes may be employed, particularly in the formation of the rotor and housing elements, all without departing from the spirit of the invention, and I therefore do not desire to be limited to that precise form beyond the limitations as may be imposed by the following claims.

I claim:

1. A rotary engine comprising a body having a circular chamber therein with an initial set of expansion cells in regular sequence circumferentially therearound and radially opening into the chamber, a second set of expansion cells in regular sequence circumferentially therearound fol-

lowing the said initial set; a rotor mounted in said chamber and having a plurality of power cells around and opening radially outwardly from the rotor periphery; all of said chamber and rotor cells having equal circumferential lengths between trailing and leading ends thereof; said body having a booster cell opening radially into said chamber between said two sets of expansion cells; and said two sets of cells having an intervening circumferential space across said booster cell differing by approximately a half circumferential length of one of said expansion cells; said intervening space being equal to at least one and one half times said expansion cell length.

2. A rotary engine comprising a body having a circular chamber therein with an initial set of expansion cells in regular sequence circumferentially therearound and radially opening into the chamber, a second set of expansion cells in regular sequence circumferentially therearound following the said initial set; a rotor mounted in said chamber and having a plurality of power cells around and opening radially outwardly from the rotor periphery; all of said chamber and rotor cells having equal circumferential lengths between trailing and leading ends thereof; said body having a booster cell opening radially into said chamber between said two sets of expansion cells; and said two sets of cells having an intervening circumferential space across said booster cell differing by approximately a half circumferential length of one of said expansion cells; said intervening space being equal to at least one and one half times said expansion cell length; said booster cell having a volume equal at least that of two of said expansion cells and a circumferential length equal to said intervening space.

3. A rotary engine comprising a body having a circular chamber therein with an initial set of expansion cells in regular sequence circumferentially therearound and radially opening into the chamber, a second set of expansion cells in regular sequence circumferentially therearound following the said initial set; a rotor mounted in said chamber and having a plurality of power cells around and opening radially outwardly from the rotor periphery; all of said chamber and rotor cells having equal circumferential lengths between trailing and leading ends thereof; said body having a booster cell opening radially into said chamber between said two sets of expansion cells; and said two sets of cells having an intervening circumferential space across said booster cell differing by approximately a half circumferential length of one of said expansion cells; an annular rib around said chamber dividing all of said expansion cells into two separate groups, one group on each side of the rib, the cells in both groups being transversely aligned; and an annular rib

around said rotor in alignment with said chamber rib to have running clearance therebetween, dividing the said rotor power cells into two groups, one of the rotor groups having its cells staggered circumferentially in respect to those of the other group.

4. A rotary engine comprising a body having a circular chamber therein with an initial set of expansion cells in regular sequence circumferentially therearound and radially opening into the chamber, a second set of expansion cells in regular sequence circumferentially therearound following the said initial set; a rotor mounted in said chamber and having a plurality of power cells around and opening radially outwardly from the rotor periphery; all of said chamber and rotor cells having equal circumferential lengths between trailing and leading ends thereof; said body having a booster cell opening radially into said chamber between said two sets of expansion cells; and said two sets of cells having an intervening circumferential space across said booster cell differing by approximately a half circumferential length of one of said expansion cells; an annular rib around said chamber dividing all of said expansion cells into two separate groups, one group on each side of the rib, the cells in both groups being transversely aligned; and an annular rib around said rotor in alignment with said chamber rib to have running clearance therebetween dividing the said rotor power cells into two groups, one of the rotor groups having its cells staggered circumferentially in respect to those of the other group; said chamber rib also dividing said booster cell into two parts.

5. A rotary engine comprising a body having a cylindrical chamber therein with an initial set of expansion cells arranged in regular sequence for a distance therearound, each of said cells opening through the circumferential wall of said chamber, each opening being equally spaced one from the other and of equal circumferential length; a booster cell in said body at the end of said initial set of expansion cells having an opening through said wall, the length of which opening is greater than that of one of said expansion cells but less than two lengths thereof; a second set of expansion cells continuing around said body from said booster cell to have openings through said wall of the same length and same spacing apart as that of the cells in said first set; and a rotor mounted in said chamber to have a periphery in close running fit with said chamber wall, said rotor having a plurality of power cells therearound each opening outwardly through said periphery by equal opening circumferential lengths.

VERNER E. SPROUSE.
